DISPLAY BOX

John K. Darragh, Astoria, N. Y., assignor to Elizabeth Heck Darragh, Astoria, N. Y.

Application December 17, 1935, Serial No. 54,822

13 Claims. (Cl. 206—44)

The present invention relates to display boxes and enclosing cartons therefor.

It is an object of the invention to provide a display box construction such that upon removing its enclosing carton from the loaded display box, the display box assumes its display position, slanting upwardly toward the rear and with its bracing easel in bracing position.

Another object is to provide in connection with such a display box, an enclosing carton provided with an easel covering flap such that when the means securing the display box in the carton is released, the easel covering flap of the carton will allow the display box easel, beginning with the first carton removing movement, to assume its display box supporting position.

A further object is to provide, in connection with the display box supporting easel, a movable display box back, which, by movement of the easel into display box supporting position, is caused to move upwardly within the box above the upper limit of the box load to bring into view, clear of the box load, a box back area that may be used for printed matter, such as advertising.

The invention consists in the features and constructions hereinafter described and claimed and illustrated in the accompanying drawing, showing, by way of example, a preferred embodiment of the invention, and in which:

Figure 1 is a top plan view of the blank from which the display box is made;

Figure 2 is a perspective front view, on a larger scale, of the box in display position;

Figure 3 is a perspective rear view of the box in display position;

Figure 4 is a vertical central sectional view through the box in display position, and taken on line 4—4 of Figure 5;

Figure 5 is a horizontal sectional view thereof taken on line 5—5 of Figure 4;

Figure 6 is a longitudinal central sectional view through the display box, filler and enclosing carton; and

Figure 7 is a plan view, on a reduced scale, showing the carton flap and method of securing the display box and filler within the carton.

The invention is illustrated in connection with a box made from a single blank of the preferred form, but of course is not limited to such construction.

Referring in detail to the drawing, the blank shown in Figure 1 comprises a box back 11 joined to which, in folding relation thereto along the dotted line 13, is the easel back support 15. The easel back support 15 has extending laterally

from it, along fold lines shown at 16, a pair of easel braces 18.

A fold line 20 separates from the easel back support 15 the easel bottom section 22 which has adjoining it and separated from it by the slotted fold line 23 the interiorly sliding box back 25 hereinafter more fully described.

Extending laterally from one side of the box back 11 are a series of box back glue tabs 27, 28 and 29.

Extending laterally from the other side of the box back 11 is a box side section 32 provided with one or more interiorly projecting article supporting tabs 33. The box side 32 is separated from the box back 11 by a fold line 34 and is in turn separated by a fold line 36 from the box front section 37. This front section is essentially an article retaining and exhibiting section, as distinguished from an article covering section and for this purpose is largely cut away from the top 20 downwardly as indicated in Figure 2. Joining the box front 37 in the cut-away area is an inside lower front section 34 and an inner bottom section 35.

Adjoining the box front 37 but on the other side thereof and separated from it by the fold line 39 is the other box side 40, which is provided with interiorly projecting article supporting tabs 41 corresponding to and for cooperation with the article supporting tabs 33 of the box side 32.

Adjoining the lower portion of the box front 37 and separated from it by the fold line 45 is the box bottom section 47 having laterally extending from it in folding relation thereto a pair of side brace sections 49.

Separated from the box bottom section 47 by the fold line 52 is the bottom back flap 53, behind which slides the lower portion of the sliding back 25 when the loaded display box is being placed in display position. This operation, as hereinafter described, can be performed simply by removing from the loaded display box its enclosing or shipping carton.

The portions of the blank of Figure 1 that are glued or similarly secured in the formed box as it appears, for example, in Figure 2, comprise the box back securing tabs 27, 28 and 29, all of which are glued or similarly secured to the free vertical edge of the box side 40; and the bottom side braces 49, which are glued or similarly secured to the lower portions of the inside faces of the box sides 32 and 40, if desired.

In assembling the display box from the blank of Figure 1, the tabs 27, 28, 29 are bent downwardly at right angles and the side 32 with its joining

sections is similarly bent along the fold line 34. The box front 37 is then bent in the same direction along the fold line 36 and the box side 40 bent along the fold line 39 to bring it into position to contact with the box back securing tabs 27, 28 and 29, which are glued or similarly secured to the inside face of box side 40.

Along fold line 23 the sliding back section 25 is bent downwardly or away from the observer as viewed in Figure 1, and the easel bottom section 22 is similarly bent and in the same direction along fold line 20. The easel back support 15, however, is bent in the opposite direction along fold line 13, that is, upwardly from the box back 11 as viewed in Figure 1. The easel braces 18 are bent downwardly at right angles as viewed in Figure 1. The sliding back may then be thrust upwardly through the open bottom of the box to lie along the interior face of the box back 11 and the easel back support, easel bottom, and easel braces 18 may be flattened against the sliding back 25 to lie in the same plane as the box back 11.

The bottom side braces 49 and bottom back flap 53 may now be bent inwardly of the bottom section 47 and the bottom brought into position with the bottom side braces adjacent the lower interior faces of the box sides to which they may, if desired, be secured, for example, with glue, and the bottom back flap 53 lying against and in sliding relation with the sliding back 25.

The inside lower front 34 is then bent through 180° to lie along the inside face of the box front 37, which brings the inner box bottom 35 into contact with the outside box bottom 47. The article supporting tabs 33 and 41 have been previously bent so that they will extend toward each other interiorly of the box.

Referring now more particularly to Figures 6 and 7, an enclosing carton 61 is provided for the display box and has the general overall shape of the display box. The enclosing carton 61 is closed at top, bottom, both sides and one end 63.

Owing to the fact that one of the features of the invention includes the slanting backward of the display box when in display position, with the bottom of the display box in alignment with the easel bottom 22, the display box bottom is not in a plane at right angles to its front and back, but is at an angle thereto, as shown in the drawing.

For this reason, there may be included in the invention as a whole a filler member 65 of the same material as the carton and having two adjoining sides 66 and 67 at right angles to each other and two faces 69 and 70 in alignment with each other and lying against the outer face of the display box bottom as shown in Figure 6. the two ends 72 and 73 of the filler member 65 being bent into contact with each other and extending into abutment with the fold line separating the right angularly adjoining sides 66 and 67 of the filler member. This may be made by folding a filler sheet, discarded when the carton is removed.

This produces a substantially rigid filler whose side 65 forms an end closure for the enclosing carton 61.

Near its end opening, one face of the carton 61, namely the face to be in contact with the display box back, is provided with a hinged flap 75 whose side edges 76 and 77 are cut out of the carton face and which is joined to the carton face by a fold line 79.

75 A piece of gummed paper 80 is secured to the

enclosing carton flap 75 and passes across the side 66 of filler 65 closing the open end of the carton and has its other end fastened to the opposite carton face as shown in Figures 7 and 6.

When the enclosing carton is to be opened 5 and the loaded display box set up in display position, the gummed paper tab 80 is broken, the filler 65 removed, and the enclosing carton set upright with the top of the loaded display box uppermost, and the open carton end supported 10 on any suitable horizontal surface. With the filler 65 removed, the enclosing carton 61 may now be lifted straight upwardly with the result that the forward lower or front bottom edge of the display box and the fold line 23 separating 15 the sliding back 25 from the easel bottom 22 contact with the supporting surface. The result is that, due to the weight of the display carton itself, and especially when it is loaded, there is a tendency for the display box to assume its display position, the box back 11 sliding 20 downwardly with respect to the back portion 25, whose bottom edge rests against the horizontal support, this movement of the display box forcing outwardly toward the rear the fold line 25 20 between the easel back support 15 and the easel bottom 22 until the outside lower face of the display box bottom contacts the horizontal supporting surface, at which moment it is in alignment with the easel bottom 22 which contacts 30 with the horizontal supporting surface at the same time. Thus by the time the enclosing carton has been removed from the display box, the display box has assumed its display position, its movement in assuming this position commencing as soon as the carton removing motion is commenced, the carton flap 75 swinging outwardly along its hinge line 79 as it is pressed 35 outwardly by the easel back support 15.

Also during the carton removing movement, 40 which causes the starting and completion of the play box movement which results in its assumption of its display box position, the relative movement between the box back 11 and the sliding back 25 brings the upper portion of the sliding back 25 upwardly beyond the upper edge of the box back 11 and consequently up above the top-most face of the display box load, thereby bringing into view above the display box load, such advertising or other printed matter as the upper portion of the sliding back 25 may carry. 45

The foregoing construction provides a display box whose own weight, upon any attempt to set it down, forces it into tilted display position; and forces the easel out into box supporting 55 position; and forces upwardly, into view above the box load, and beyond the limits of the box proper, a sliding back presenting a display area for printed matter such as advertising.

Moreover, the construction is such that merely lifting off the covering or enclosing carton causes 60 the weight of the box to accomplish the foregoing results, and, in doing so, to bring the display box bottom and the easel bottom into alignment with each other, thus providing the box 65 with an extended bottom insuring, despite its tilting backward, that it will remain in stable equilibrium in display position.

It will be understood that the present invention is not limited to embodiment in a construction made from a single blank, but that single or multiple blanks of other forms than that shown may be used, and that certain features of the complete preferred embodiment shown may be omitted and other modifications 75

made within the invention as defined by the appended claims.

What is claimed is:

1. A package comprising a tilting display box, an enclosing carton and releasable means for holding the box in the carton, said box having a slanting bottom, said enclosing carton having an open bottom when the box holding means is released and movable upwardly off the box to leave it free of the carton in an upright position of unstable equilibrium, and said box having at its back a supporting device movable into box supporting position by the box weight when the box, released from its carton, seeks a position of stable equilibrium, said supporting device including an easel member having a back support and a bottom section in hinged relation therewith, a sliding member associated with the box back and movable below the box bottom, said bottom section being hingedly attached thereto. 5
2. A package comprising a tilting display box, an enclosing carton and releasable means for holding the box in the carton, said box having a slanting bottom, said enclosing carton having an open bottom when the box holding means is released and movable upwardly off the box to leave it free of the carton in an upright position of unstable equilibrium, said box having at its back a supporting device movable into box supporting position by the box weight when the box, released from its carton, seeks a position of stable equilibrium, and said enclosing carton having a hinged portion overlying said supporting device and movable outwardly thereby when the carton, while being withdrawn, allows the box to commence its movement into tilted display position of stable equilibrium. 10
3. A package comprising a tilting display box, an enclosing carton and releasable means for holding the box in the carton, said box having a slanting bottom, said enclosing carton having an open bottom when the box holding means is released and movable upwardly off the box to leave it free of the carton in an upright position of unstable equilibrium, said box having at its back a supporting device movable into box supporting position by the box weight when the box, released from its carton, seeks a position of stable equilibrium, said enclosing carton having a hinged portion overlying said supporting device and movable outwardly thereby when the carton, while being withdrawn, allows the box to commence its movement into tilted display position of stable equilibrium, and a separate filler member closing the open carton end releasable therefrom by said releasable means. 15
4. A package comprising a tilting display box, an enclosing carton, and releasable means for holding the box in the carton, said box having a slanting bottom, said enclosing carton having an open bottom when the box holding means is released and being movable upwardly off the box to leave it free of the carton in a substantially upright position of unstable equilibrium, and said box having a sliding back and a supporting device associated therewith movable into box supporting position by the box weight when the box, released from its carton, seeks a position of stable equilibrium, said supporting device, by such movement causing said back to slide upwardly of the box. 20
5. A package comprising a tilting display box, an enclosing carton, and releasable means for holding the box in the carton, said box having a slanting bottom, said enclosing carton having an open bottom when the box holding means is released and being movable upwardly off the box to leave it free of the carton in a substantially upright position of unstable equilibrium, and said box having a bottom section and a propping section associated therewith movable into box supporting position by the box weight when the box, released from its carton, seeks a position of stable equilibrium, said supporting easel, by such movement causing said back to slide upwardly of the box and bring the slanting bottom of the box and the easel bottom section into horizontal alignment. 25
6. A tilting display box having a slanting bottom and having a sliding back and, associated therewith, a supporting device including an easel member having a back support hinged to the box, and a bottom section hinged to said back support and hinged to said sliding back, said back support and bottom section being movable to substantially flat position with respect to the back of the box, with said bottom section extending below the adjacent back edge of the box bottom, said bottom section being actuated by the box weight, when the box is placed upright, to force the back support away from the box back into box supporting position and thereby slide said back upwardly of the box. 30
7. A tilting display box having a slanting bottom and having a sliding back and, associated therewith, a supporting device including an easel member having a back support hinged to the box, and a bottom section hinged to said back support and hinged to said sliding back, said back support and bottom section being movable to substantially flat position with respect to the back of the box, with said bottom section extending below the adjacent back edge of the box bottom, said bottom section and said slanting bottom being brought into alignment by the box weight, when the box is placed upright, to force the said support away from the box back into box supporting position, and thereby slide said back upwardly of the box. 35
8. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position below the box bottom into supporting position in the plane of the box bottom. 40
9. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position below the box bottom into supporting position in the plane of the box bottom, said display box and easel device being made from a single blank and being foldable flat for packing. 45
10. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position 50
11. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position 55
12. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position 60
13. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position 65
14. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position 70
15. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position 75

below the box bottom into supporting position in the plane of the box bottom, said easel device being foldable against the box for shipping.

11. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position below the box bottom into supporting position in the plane of the box bottom, said easel device having foldable stiffening flanges.
15. 12. A tilting display box having a slanting back and a bottom and having a self setting easel device moved into box supporting position by the box weight, said easel device comprising a supporting member attached to the box back and provided with a base portion in hinged relation therewith and movably attached to the box and having an edge movable from a shipping position

below the box bottom into supporting position in the plane of the box bottom, said box having article supports extending toward each other from opposite box side walls, and the display box and easel device being made from a single blank and foldable flat for packing.

13. A tilting display box having a self-setting easel movable by the box weight into box supporting position from a shipping position substantially flat against the box, said box having a bottom and a slanting sliding back, and said self-setting easel including a back support hinged to the box, and a bottom section hinged to said back support and hingedly associated with said slanting sliding box back, said bottom section in shipping position extending below the box bottom, and being movable by the box weight into alignment with the box bottom, thereby shifting said back support into box supporting position and said slanting sliding back into display position.

JOHN K. DARRAGH.
